H. FINCKH.
WINDOW SCREEN.
APPLICATION FILED JULY 19, 1921.

1,436,952.

Patented Nov. 28, 1922.

UNITED STATES PATENT OFFICE.

HENRY FINCKH, OF BROOKLYN, NEW YORK.

WINDOW SCREEN.

Application filed July 19, 1921. Serial No. 435,974.

To all whom it may concern:

Be it known that I, HENRY FINCKH, a citizen of the United States, and residing at Flatbush, Brooklyn, in the county of 5 Kings and State of New York, have invented certain new and useful Improvements in Window Screens, of which the following is a specification, such as will enable those skilled in the art to which it appertains to 10 make and use the same.

This invention relates to what are known as window screens, and the object thereof is to provide an improved device of this class, the construction and arrangement of which 15 is such that one side portion of the frame is adjustable laterally and may be locked in its outermost position so as to securely lock and hold the screen or screen frame in the window, and with this and other objects in 20 view the invention consists in a device of the class specified, constructed and operated as hereinafter described and claimed.

The invention is fully disclosed in the following specification, of which the accompanying drawing forms a part, in which the separate parts of my improvement are designated by suitable reference characters in 25 each of the views, and in which:—

Fig. 1 is a side view of my improved window screen;

Fig. 2 a central vertical section of one side portion thereof;

Fig. 3 a section on the line 3—3 of Fig. 2; and,

Fig. 4 a section on the line 4—4 of Fig. 2.

In the drawing forming part of this specification, I have shown at *a* an ordinary window screen comprising top and bottom frame members *a*² and *a*³ and side frame 40 members *a*⁴ and *a*⁵.

The top and bottom frame members and the side member *a*⁴ are or may be constructed in the usual or any desired manner, and secured therein is a wire mesh body *b* which 45 may also be formed and secured in position in any desired manner, and this wire mesh body *b* is secured in the frame adjacent to the back part thereof, as clearly shown in Figs. 3 and 4.

50 The side frame member *a*⁵ of the frame is composed of two separate parts, said frame member being divided vertically, the outer part *a*⁶ thereof being movable toward and from the inner part, and said outer part *a*⁶ is provided in the inner face thereof with a deep vertical groove *a*⁷, which is rectangu-

lar in cross section and within which the outer portion of the part *a*⁸ fits as clearly shown at *a*⁸, and with this construction the part *a*⁶, is movable inwardly and outwardly 60 on the part *a*⁵.

The stationary part *a*⁵ of the frame is provided centrally thereof with a central vertical slot *a*⁹, and in the top portion of which is pivoted as shown at *c* a crank lever *d* having a V-shaped or U-shaped portion *d*² which operates in said slot and which is adapted to bear on the outer wall of the slot *a*⁹ in the movable part *a*⁶ of the frame and secured to said wall, in the construction shown, is a 70 metal plate *e* on which the part *d*² of the crank lever is adapted to bear, and the lower member of the V-shaped or U-shaped portion *d*² of the crank lever is provided with an arm *d*³ by which said crank lever is manipulated, and which is adapted to engage a hook or retaining device *f* secured to or in the part *a*⁵ of the screen frame. 75

The movable part *a*⁶ of the screen frame is provided with pins *g* which are movable into 80 and out of sockets *g*² formed in the part *a*⁵ of the screen frame, and which serve as guides and retainers for said part *a*⁶ in its inward and outward movement, and the part *a*⁵ of the screen frame is also provided with 85 horizontal slots *h*, and passed therethrough and through the side walls *h*² of the slot *a*⁹ in the part *a*⁶ of the screen frame are bolts *i*, which are freely movable in the slots *h* and permit of the inward and outward movement of the part *a*⁶, while at the same time locking it to the part *a*⁵. 90

It will be understood that the window frame in connection with which my improved screen is employed, but which is not 95 shown, is provided in the sides and the bottom thereof with grooves in which the screen frame fits when in use, and with my improvement, when the part *a*⁶ of the screen frame is in its innermost position, in which 100 the crank lever *d* assumes the position shown in dotted lines in Fig. 2, the screen frame may be easily inserted into the desired position in the window frame, after which the crank lever *d* is swung into the 105 position shown in Fig. 2 and locked therein, and in this operation the part *a*⁶ of the screen frame is forced outwardly by said crank lever into firm contact with the adjacent side of the window frame, and this 110 locks the screen frame in said window frame, and when it is desired to remove the screen

frame from the window frame, all that is necessary is to unlock the crank lever d and swing it into the position shown in dotted lines in Fig. 2, after which the main part 5 of the screen frame may be moved to the left or in the direction of the part a^6 thereof, and this operation will shorten the screen frame so that it may be removed from the window frame as will be readily understood.

10 My invention is not limited to any specific form or construction of the main frame, all that is necessary being to provide the part a^5 thereof with the movable part a^6 15 and other details of construction which will render the device operative, as herein shown and described, and changes in and modifications of the details of construction herein shown and described may be 20 made, within the scope of the appended claims, without departing from the spirit of my invention or sacrificing its advantages.

Having fully described my invention, what I claim as new and desire to secure 25 by Letters Patent, is:—

1. A window screen one side portion of 30 which is provided with a vertical slot, a movable part mounted on said side portion and movable outwardly and inwardly thereon, a crank lever pivoted to said side portion within said slot and adapted to frictionally engage with said movable part to hold it in an extended position, and said lever being provided with integral means which extends 35 inwardly of said side portion and by means of which said lever is operated.

2. A window screen one side portion of which is provided with a vertical slot, a movable part mounted on said side portion and movable outwardly and inwardly thereon, a crank lever pivoted to said side portion within said slot and adapted to operate in connection with said movable part to hold it in an extended position, said lever being provided with an arm which extends 40 inwardly of said side portion and by means of which said lever is operated, and means cooperating with said arm for holding the same in a predetermined position.

3. A window screen one side portion of 45 which is provided with a vertical slot, a movable part mounted on said side portion and movable outwardly and inwardly thereon, a crank lever comprising a V-shaped head portion, an arm portion extending inwardly of said side portion of the screen, the head portion of said lever being pivoted to said side portion of the screen with in said slot and the V-shaped portion thereof being adapted to operate in connection 50 with said movable part, means cooperating with the arm portion of said lever for holding the same in a predetermined position, and means for limiting the movement of 55 said movable part.

In testimony that I claim the foregoing as my invention I have signed my name in presence of the subscribing witness this 18th day of July 1921.

HENRY FINCKH.

Witness:

C. E. MULREANY.
